UNITED STATES PATENT OFFICE.

WILLIAM E. SMITH, OF LYNN, MASSACHUSETTS, ASSIGNOR TO BOSTON MACHINE WORKS COMPANY, OF LYNN, MASSACHUSETTS, A CORPORATION OF MASSACHUSETTS.

BEADING-MACHINE.

1,244,650.

Specification of Letters Patent. Patented Oct. 30, 1917.

Application filed October 28, 1916. Serial No. 128,320.

To all whom it may concern:

Be it known that I, WILLIAM E. SMITH, a citizen of the United States, residing at Lynn, county of Essex, State of Massachusetts, have invented an Improvement in Beading-Machines, of which the following description, in connection with the accompanying drawing, is a specification, like characters on the drawing representing like parts.

This invention relates to beading machines such as are used for pressing or setting a folded edge of fabric, leather, etc., and the object of the invention is to provide a novel beading machine having provision for heating the anvil or work support. The advantage of this is that the fold or bead will be more permanently set due to the fact that the goods become heated slightly by contact 20 with the heated anvil as they are operated upon.

In the embodiment of the invention herein illustrated, the heating element is constructed to encircle or surround the anvil, and it is so supported that it is not affected by the hammer-like blow which is given to the anvil by the hammer or pressing element.

In order to give an understanding of my invention, I have illustrated in the drawings 30 a selected embodiment thereof which will now be described, after which the novel features will be pointed out in the appended claims.

Figure 1 of the drawings is a side view 35 of a beading machine embodying my invention;

Fig. 2 is an enlarged detail view of the anvil and the means for heating the latter. 1 indicates the frame of the machine in 40 which is journaled a driving shaft 2 that may be operated by any suitable means as by means of a driving pulley 3. 4 indicates the anvil or work support over which the work is fed, and 5 is the hammer or presser element. The anvil is provided with the usual rounded end on which the work rests and the hammer element is shown as carried by an arm or lever 6 pivotally mounted to the frame at 7. The hammer is constructed 45 to be vibrated rapidly toward and from the anvil 4, and for this purpose the driving shaft is provided with an eccentric 8, the eccentric strap 9 of which is connected to the lever 6 by the link or connection 10. 50 As the shaft 2 rotates rapidly, the hammer 55

element 5 will be given a vibrating movement toward and from the anvil 4, and as the folded edge of the sheet material is fed over the anvil, the hammer 5 will give said edge a series of repeated blows in rapid 60 succession, thereby setting the fold.

The parts thus far described are or may be all as usual in beading machines of this nature and form no part of the present invention.

As stated above, my present invention relates to a means for heating the anvil 4 so that as the work is fed over the anvil, it will be heated somewhat, thus making the action of the machine more effective in giving a permanent set to the folded edge. I will preferably use electrical heating means for this purpose in the form of a heating coil which surrounds the anvil, and in order to prevent injury to the coil by the hammer-like blows which are received by the anvil, I propose to so mount the heating coil that it will not be affected by the blows of the hammer element 5.

The heating coil is shown at 11 and it 80 is contained within a holder 12 which encircles the anvil 4, the heating coil being confined between the inner wall 13 of the holder and a tubular shell 14. The turns of the heating coil are insulated from the holder 85 by insulation 31 and are insulated from each other by some suitable insulating compound which is a good conductor of heat. The heating coil is connected to feed wires 15 by which a proper amount of electric current 90 is delivered to the coil.

The anvil 4 is backed by a spring 16 which rests on the head 17 of a stud 18 that is screw-threaded into the frame 1. The holder 12 is formed with a recess 19 95 which not only receives the anvil 4, but also receives the spring 16 above referred to. The holder is also formed with the flange 20 at its lower end which engages the under side of the head 17 and which retains the 100 holder in place. The outer end of the holder is provided with the inwardly-directed annular flange 21 which overlies a rib or flange 22 formed on the anvil and which thereby limits the outward movement of the anvil. 105 This flange 21 is shown as formed on a ring-like member 23 which is screw-threaded to the outer end of the holder, this construction being adopted for convenience in manufacture and assembling of the parts. The 110

holder is also provided with a positioning pin 24 which enters a recess 25 formed in the frame, said pin operating to prevent the holder from turning movement.

5 The normal expansive action of the spring 16 serves to keep the flange 22 of the anvil against the flange 21 and to hold the flange 20 of the holder in contact with the head 17 of the stud 18, as shown in Fig. 2. The 10 anvil and the holder are so constructed that the anvil can have a limited depressing movement relative to the holder without bringing the flange 22 against the end 250 of the heating coil. The purpose of this 15 construction is to permit the anvil to yield slightly at each blow of the hammer independently of the holder, so that the force of the blow will be received directly by the anvil and transmitted therefrom through 20 the spring 16 to the frame, instead of being transmitted to the holder 12 or the heating unit 11. The machine is, therefore, capable of continued and rapid operation without danger of injuring the insulation or any 25 other part of the heating unit.

It will be noted that the stud 18 is screw-threaded into the frame 1. The purpose of this is to provide for adjusting the anvil and holder bodily relative to the hammer 30 element 5 to correspond to different thicknesses of work. The construction is such that in all adjusted positions of the anvil the latter is always capable of a limited yielding movement relative to the holder and the heating unit, and hence there is no 35 danger of the heating unit becoming injured in any adjusted position of the anvil.

While I have illustrated herein a selected embodiment of my invention, I do not wish 40 to be limited to the constructional features shown.

I claim:

1. In a beading machine, the combination with a frame, of an anvil, a spring yieldingly sustaining said anvil, a vibratory hammer, a member encircling the anvil and limiting its spring-pressed movement, said member being capable of movement relative to the frame, and means carried by 45 said member for heating the anvil.

2. In a beading machine, the combination with a frame, of an anvil, a spring yieldingly sustaining said anvil, a vibratory hammer, a member encircling the anvil and limiting its spring-pressed movement, said member being capable of movement relative to the frame, and means carried by 50 said member for heating the anvil.

to the frame in the direction of the movement of the hammer, and means carried by said member for heating the anvil.

3. In a beading machine, the combination 60 with a frame, of an anvil, a spring yieldingly sustaining said anvil, a vibratory hammer co-operating with the anvil, a member encircling the anvil and limiting its spring-pressed movement, said member being capable of movement in the direction of the 65 yielding movement of the anvil, and electrical means carried by said member for heating the anvil.

4. In a beading machine, the combination 70 with a frame, of an anvil yieldingly sustained thereby, a vibratable hammer element, and a heating element surrounding the anvil element and capable of movement relative to the frame, said anvil element 75 being yieldable relative to the heating element under the impact of the hammer element.

5. In a beading machine, the combination with a frame, of an anvil element yieldingly 80 sustained thereby, a vibratable hammer element, a holder surrounding the anvil element and capable of movement relative to the frame, and a heating unit carried by 85 the holder and encircling the anvil, said anvil being yieldable relative to the heating unit under the impact of the hammer element.

6. In a beading machine, the combination with a frame, of an anvil element yieldingly 90 sustained thereby, a vibratable hammer element, a heating element surrounding the anvil element, the latter being yieldable relative to the heating element under the impact of the hammer element, and means for 95 adjusting the anvil element and heating element relative to the hammer element.

7. In a beading machine, the combination with a frame, of a stud adjustably secured 100 therein, a holder secured to said stud and provided with a recess, an anvil element yieldingly sustained in said recess, and a heating unit carried by the holder element and encircling the anvil element, said holder having means to limit the outward movement of the anvil element due to the action of the spring and the anvil element being capable of a yielding movement relative to the holder element.

In testimony whereof, I have signed my 110 name to this specification.

WILLIAM E. SMITH.
